UNITED STATES PATENT OFFICE.

WILLIAM JOHN CROWLE, OF EASTON, PENNSYLVANIA.

BOX-MOTION FOR LOOMS.

1,351,099.

Specification of Letters Patent. Patented Aug. 31, 1920.

Application filed March 4, 1920. Serial No. 363,145.

To all whom it may concern:

Be it known that I, WILLIAM JOHN CROWLE, a citizen of the United States, residing at Easton, in the county of Northampton and State of Pennsylvania, have invented new and useful Improvements in Box-Motions for Looms, of which the following is a specification.

This invention relates to improvements in box motions for looms, and particularly to improvements in shuttle-box actuating or controlling means for the raising and lowering of the boxes at the right periods for the manufacture of cloth requiring two picks each of a right and left twist thread or two picks each of two colors.

One object of my invention is to provide novel and simplified means, in place of the numerous parts heretofore employed, for raising and lowering the shuttle-box or boxes at proper periods.

Another object of the invention is to provide shuttle-box actuating or controlling means which is adapted for use on either or both sides of the loom.

Still another object of the invention is to provide shuttle-box actuating or controlling means which may be employed in duplicate for controlling sets of boxes on both lay ends, one set of controlling means acting one pick ahead of the other, whereby the loom may be adapted for weaving cloth requiring one pick each of three different colors or twist threads.

The invention consists of the features of construction, combination and arrangement of parts, hereinafter fully described and claimed, reference being had to the accompanying drawings, in which:

Figure 1 is an end elevation of the head motion of a loom embodying my invention.

Fig. 2 is a view in side elevation of parts of the head motion.

Fig. 3 is a vertical longitudinal section on line 3—3 of Fig. 1.

Fig. 4 is a vertical longitudinal section on line 4—4 of Fig. 1, showing particularly my improved shuttle-box actuating means.

Fig. 5 is a view of parts of the mechanism illustrated in Fig. 4 on an enlarged scale and with the actuating lever and cam in a different position.

Fig. 6 is a top plan view of the parts shown in Fig. 1.

Referring to the drawings, 1 designates a portion of the main frame of the loom; 2, the

loom arch or head stand; 3 and 4, the upper and lower cylinder gear shafts carrying the upper and lower cylinder gears 5 and 6; 7, the vibrator gears; 8, the vibrator levers; 9, the harness jacks coupled to the vibrator gears by the connectors 10; 11, the pattern chain cylinder shaft carrying gears 12 driven by pinions 13 on the shaft 4; 14, the pattern chain; and 15, a cross rod pivotally supporting the levers 8 at their rear ends. These parts may be of the ordinary type employed in looms in common use.

My attachment comprises a shuttle-box actuating or controlling lever 16 pivotally mounted at one end 17 on the cross rod 15 and provided at its opposite end with an elongated slot 18. Intermediate its ends the lever is provided with a contact member in the form of a friction roller 19 for co-operation with a shuttle-box actuating or controlling cam 20. The cam 20 comprises a substantially quadrantal disk loosely mounted on the shaft 11 at one side of one of the gears 12 and fixed to said gear for rotation therewith by a screw or other suitable fastening device 21. The cam has an inner curved contact surface 22, an outer or peripheral curved contact surface 23, and straight side surfaces 24 and 25 for co-operation with the friction roller 19.

The lever 16 is periodically moved upward and downward or vibrated through the action of the cam to successively raise and lower the shuttle-boxes. This lever is shown as suitably connected to a shuttle-box 26 movable in a suitable guide 26'. The connecting means shown in the present instance (see Fig. 4) comprises a chain or like flexible connection 27 secured at one end to the slotted end 18 of the lever and at its opposite end to a bracket member 28, said chain being properly trained over guide pulleys 29. The bracket member 28 is fixed to a lifter rod 30 attached to the shuttle-box 26 and itself slidably mounted for movement in a vertical plane in a stationary guide bracket 31 suitably mounted on the main frame 1 of the loom. Surrounding the lifter rod 30 between the guide 26' and the bracket member 28 is a coiled cushioning and retracting spring 32, adapted to be compressed on the upward movement of the rod 30 and operating by expansion to move the rod and shuttle-box carried thereby downward. The end of the chain 27 attached to the slot 18 of the lever 16 is connected

with a threaded stem or bolt 33 slidably mounted in the slotted end 18 and adapted to be secured in adjusted position by a nut 34, the arrangement being such that the 5 point of attachment of the chain 27 to the lever with relation to the pivoted end of the lever may be varied, to correspondingly vary the amount of motion transmitted on each movement of the lever to the shuttle- 10 box, as conditions in service may require.

Fig. 4 shows the lever 16 at the limit of its upward or shuttle-box raising movement, and Fig. 5 shows the lever at or near the limit of its downward movement in which 15 the shuttle-box is in lowered position. When the cam 20 raises the lever and moves the chain 27 an up pull is transmitted to the bracket member 28 to lift the rod 30 and compress the spring 32, which raises the 20 shuttle-box a prescribed degree in an obvious manner. When the lever 16 descends and relaxes the chain 27, the spring 32 expands, depressing the lifter rod 30 and returning the shuttle-box to its normally lowered 25 position. The formation of the cam 20 is such that the shuttle-box is in its lowered position when the friction roller 19 traverses the cam surface 22 and begins to traverse the cam surface 24, the lever being in 30 its lowermost position when the roller is at the point of intersection of said surfaces. As the cam rotates in the direction of the arrow shown in Fig. 5 from the lowest or starting 35 point mentioned, the surface 24 traveling in contact with the friction roller 19 gradually raises the lever 16 until the friction roller reaches the adjacent point of the cam surface 23, whereby the shuttle will be gradually elevated and maintained in an elevated 40 position in the travel of the friction roller over the surface 23 and until it reaches the outer edge of the surface 25. In its travel along the cam surface 25 toward the surface 22 the lever 16 is lowered and maintained in 45 lowered position until again raised by the cam surface 24. When the lever is lowered the first shuttle-box will be in position for operation and will dwell there until the shuttle carrying the one twist thread or color 50 for two picks is thrown across the shed. When the lever is elevated the second shuttle-box will be raised to operative position and dwell there while the shuttle carrying the other twist thread or color is shot across 55 the shed, so that on each complete revolution of the cam the first and second shuttle-boxes will be alternately and successively moved into operative position for the proper action of the loom mechanism in the weaving 60 of cloth requiring two picks each of a right and left twist thread or two picks each of two colors.

The parts referred to constituting my invention are adapted to be employed in the 65 place of the mechanism commonly used, con-

sisting of balls, sinkers, links and equivalent devices which are subject to rapid wear and tear and quickly get out of order, my invention providing a simple, reliable and efficient type of means for actuating and controlling the shuttle-box which is durable and not liable to easily get out of order, and whereby reliability of action and the efficiency of the loom will be materially increased.

Where but a single set of shuttle-boxes is employed at one side of the loom, a single lever and cam is employed for use in connection therewith, but this lever and cam may be arranged on either side of the loom, according to the arrangement of the shuttle-boxes, by simply reversing the position of the cam 20, that is, securing it by means of its fastening screw 21 in a proper manner to one or the other of the gears 12, as the case 85 may be. In practice, my attachment also lends itself to another and important use, in that by employing two levers 16 and two cams 20 at opposite sides of and actuated by a gear 12 at one side of the loom, for coöperation with two sets of shuttle-boxes raised and lowered at proper times by the respective levers, and arranging one cam so that it will be one pick ahead of the other, the shuttle-boxes may be properly controlled to 90 adapt the loom for weaving a piece of cloth that requires one pick each of three different colors or twist threads.

In the present instance I have shown the application of my invention to the Gem 100 head motion of a loom of the Crompton & Knowles type, but it is to be understood that I do not limit the invention to this or any other type of loom, but reserve the right to apply it to any type of loom to which it is 105 applicable. Also it is to be understood that the gears 12 may be made of various characters and the levers 16 of various lengths as may be required in the application of the invention to different sizes or types of looms 110 or to suit any required or special conditions.

Having thus fully described my invention, I claim:

1. In a loom, shuttle-boxes, and shuttle-box raising and lowering mechanism including a lower cylinder gear shaft, of a vibrator gear shedding mechanism, a pattern chain cylinder shaft, gearing between said shafts, a vibratory lever, a cam actuated by said gearing for periodically raising and lowering the lever, and connecting means between the lever and the shuttle-boxes.

2. In a loom, shuttle-boxes, a lower cylinder gear shaft, a pattern cylinder shaft, intermeshing gears on said shafts, a vibratory lever, a cam loose on the pattern cylinder shaft and fixed to the gear thereon, said cam being adapted to periodically raise and lower the lever, and connecting means between said lever and the shuttle-boxes.

3. In a loom, shuttle-boxes, harness mechanism, vibrator lever operating means for actuating the harness mechanism alternately in opposite directions, a vibratory shuttle-box operating lever, a cam operated by a part of said vibrator lever operating means and having surfaces for periodically engag-

ing and raising and lowering the shuttle-box operating lever, and connecting means between the shuttle-box operating lever and the shuttle-box.

In testimony whereof I affix my signature.

WILLIAM JOHN CROWLE.
